US0D1084832S

(12) **United States Design Patent** (10) **Patent No.:** **US D1,084,832 S**
(45) **Date of Patent:** **** Jul. 22, 2025**

(54) **FIBER WINDER**

(71) Applicant: **Jameson, LLC**, Clover, SC (US)

(72) Inventors: **Carlos Becerra Alvarado**, Charlotte, NC (US); **Benjamin Erwin**, Rock Hill, SC (US); **Blake Tomlinson**, Statesville, NC (US)

(73) Assignee: **Jameson, LLC**, Clover, SC (US)

(**) Term: **15 Years**

(21) Appl. No.: **35/520,011**

(22) Filed: **Jan. 25, 2024**

(80) **Hague Agreement Data**

Int. Filing Date: **Jan. 25, 2024**

Int. Reg. No.: **DM/235060**

Int. Reg. Date: **Jan. 25, 2024**

Int. Reg. Pub. Date: **Feb. 16, 2024**

(51) **LOC (15) Cl.** **08-11**

(52) **U.S. Cl.**

USPC **D8/358**

(58) **Field of Classification Search**

USPC D6/466, 582; D8/356, 354, 388, 323, D8/324, 330, 325, 327, 331, 36, 353, D8/338; D13/155, 123, 133, 148, 149, D13/151, 184
